SUPERHEATING OF STEAM IN STEAM GENERATING INSTALLATIONS
FOR HIGH PRESSURE AND HIGHLY SUPERHEATED STEAM

UNITED STATES PATENT OFFICE.

OTTO H. HARTMANN, OF CASSEL-WILHELMSHOHE, GERMANY, ASSIGNOR TO SCHMIDT'SCHE HEISSDAMPF-GESELLSCHAFT MIT BESCHRANKTER HAFTUNG, OF CASSEL-WILHELMSHOHE, GERMANY, A CORPORATION OF GERMANY.

SUPERHEATING OF STEAM IN STEAM-GENERATING INSTALLATIONS FOR HIGH-PRESSURE AND HIGHLY-SUPERHEATED STEAM.

Application filed March 12, 1927, Serial No. 174,964, and in Germany April 14, 1926.

- My invention comprises improvements in and relating to the superheating of steam in steam plants. It has already been proposed to superheat high-pressure live steam first in a boiler-flue superheater and then to raise to a high temperature of superheat the intermediate steam still at a comparatively high pressure passing from the high-pressure additional or super-stage of the steam engine to the succeeding normal pressure stage, after which it passes into a second boiler-flue superheater to be re-superheated to the necessary temperature and led to the high-pressure super-stage of the engine.
- Where very high steam pressures of 50 to 100 atmospheres and more are concerned, and especially where the highest possible superheats are to be obtained, for example, high superheats as far as possible equal both in the high-pressure or super-stage and also in the succeeding normal pressure stage of the engine, the said proposed arrangement is in some respects inadequate.
- In order to provide for such inadequacies and at the same time essentially to simplify the installation by reducing the number and length of the superheated-steam pipes, the present invention avoids the second boiler-flue superheater and replaces it by a separate extra-high-pressure boiler, in which, in order to effect a part of the intermediate superheating, saturated steam is generated at a pressure considerably higher than that corresponding to the desired temperature of superheat.
- In a steam plant according to my invention there is a high-pressure boiler associated with one, two or more working boilers each with a single boiler-flue superheater, heating steam being generated in this high-pressure boiler at a considerably higher pressure than in the remaining boilers, so that it may be utilized for effecting part of the intermediate superheating, the other part being effected by the live steam generated in the working boiler and superheated in the flue superheater.
- The drawing shows diagrammatically a steam plant according to my invention.
- In the constructional form shown by way of example each high-pressure working boiler, 1, of a group or battery of boilers, is provided with a steam drum, 2, and boiler-flue super-
- heater 4. From the boiler-flue superheaters, the highly superheated live steam of, for example, 65 atmospheres pressure passes first through the pipe, 6, into the heating coil system of the second stage, 7, of the reheat or intermediate superheater, thereby effecting a part of the intermediate superheating, and is thence led direct through the pipe, 24, into the super-stage, 9, of the engine. In a high-pressure boiler, 25, saturated steam is generated in a coil, 26, at a considerably higher pressure, for example, at 150 atmospheres, and at a correspondingly higher temperature before superheating than the steam generated in the working boilers 1. The steam generated in this higher-pressure boiler, 25, provides the heating steam for the first stage, 27, of the intermediate superheater, to the heating coils of which it is led through the pipe, 28. The condensate from the heating coils of this first stage of the intermediate superheater is fed by a pump, 29, into the steam generating coil, 26, of the higher-pressure boiler, 25, by way of the pipe, 30. The exhaust from the super-stage, 9, of the engine, passes through the pipe, 8, and successively through the two stages, 27 and 7, of the intermediate superheater to the succeeding stage, 11, of the engine.
- My invention has the advantage that the degree of superheat, both for the high-pressure stage or super-stage of the engine and also for the succeeding stage, is increased while at the same time the installation is simplified by omitting or reducing the length of certain of the superheated-steam pipes, due to the arrangement of an additional separate boiler working at a higher pressure.
- It will be obvious that the structure described above is applicable not only to a battery of boilers as shown but to a single-boiler installation.
- What I claim is:—
- In a steam plant, the combination of a steam engine having a superstage and a second stage, a plurality of boilers generating the working steam for said superstage, each of said boilers having a boiler-flue superheater to superheat said working steam, a two-stage reheat between the superstage and the normal stage and adapted to superheat the exhaust steam from said superstage, and a high-pressure

boiler adapted to generate heating steam for the first stage of the reheater at a pressure considerably above that of the working steam, the second stage of the reheater comprising a two-path heat exchanger one path of which is connected to the first stage of the superheater and to the second stage of the engine, the other path of which is connected to said plurality of boilers and to the said superstage. In testimony whereof I have affixed my signature.
